STOVE

Bertrand B. Kahn, Cincinnati, Ohio, assignor to
 The Estate Stove Company, Hamilton, Ohio, a
 corporation of Ohio

Application February 28, 1931, Serial No. 519,211

15 Claims. (Cl. 126—41)

This invention relates to stoves and more particularly to a construction having to do with ovens therefor.

One of the principal objects of the invention is to provide an improved construction in a stove for facilitating the handling of the foodstuffs; and permitting of suitably inspecting, positioning and handling of the foodstuffs even while the oven is being heated.

Another object of the invention is to provide an oven arrangement comprising a slidable drawer containing a food supporting member, and means for adjusting the food supporting member vertically independently of the drawer sliding mechanism.

Other objects and advantages of the invention will be apparent from the description thereof set out below and from the accompanying drawings and the appended claims.

In the drawings—

Fig. 1 is a fragmentary front elevational view of a stove including a preferred embodiment of the invention with parts broken away to show details of the mechanism;

Fig. 2 is a horizontal sectional view of the removable drawer taken on the line 2—2 of Fig. 3;

Fig. 3 is a vertical sectional view along the line 3—3 of Fig. 1 showing the oven drawer in closed position;

Fig. 4 is a vertical sectional view of the inner end of the drawer taken on the line 4—4 of Fig. 2 showing details of mechanism;

Fig. 5 is a partial front elevational view of a modified form of oven;

Fig. 6 is a partial side elevational view of the oven shown in Fig. 5;

Fig. 7 is a partial front elevational view of another modified form of oven; and

Fig. 8 is a partial side elevational view of the oven shown in Fig. 7.

In the drawings, which illustrate a preferred embodiment of the invention, as incorporated in a stove, the main body of the stove is designated by the numeral 10, one of the several supporting legs of which is shown at 11. The main body of the stove and the remaining features thereof need not be shown to afford a complete disclosure of this invention and therefore only a small fragment of the stove body surrounding a single oven, is shown. The legs 11 are conveniently made adjustable in height so that the stove may be positioned at just the right height for the individual operator. Suitable heat insulating material is provided for exposed oven walls, as in-

dicated by the numeral 12, such material being of any suitable, known character.

The oven is provided with a slidable and preferably removable drawer member which carries mechanism for supporting the broiler pan or tray 5 in vertically adjustable relationship within the drawer member. This drawer member comprises a front member forming a closure for the compartment when the drawer is in closed position, and having spaced walls 15 and 16, between 10 which is heat insulating material, and which forms a closure for the broiler compartment when the drawer member is closed.

A metal plate 18 is bolted by suitable bolts 19 to the end wall 16 and spaced therefrom a sufficient distance to form a compartment housing the pan elevating mechanism, the sides and top of the plate being bent at right angles to its face so that the mechanism is completely enclosed. The inner end of the drawer is formed by bolt- 20 ing together two bent sheets of metal 20 and 21, the former also being provided with right angularly bent side and top portions so that between them they form an enclosed compartment for the pan elevating mechanism at this end of the 25 drawer.

The sides of the drawer are shallow and are formed of metal strips 22 which are bent outwardly at their upper edge to form a flange 23 and are bent inwardly at the lower edge 24 to 30 form a supporting portion. The plate 18 is formed with right angularly bent projections 25 at its lower portion which are attached to the support 24 in a convenient manner such as by welding. Likewise the metal sheets 20 and 21 35 forming the inner end wall of the drawer are made with right angularly bent projections 26 and 27 which are also welded to the support 24. Rollers 28 are mounted on the vertical portion of the strips 22 at the inner end thereof and 40 form the support for the inner end of the drawer member.

A track member is mounted within the oven compartment, this track being shown as a strip of metal 30 having a bent over flange 31 which 45 is attached to the interior wall of the broiler compartment by suitable means, such as rivets 32, the body portion being thus spaced therefrom a short distance. This metal strip extends along the compartment wall from the front to 50 back and the lower portion is bent to form a horizontally extending portion 33 which serves as a track upon which the rollers 28 supporting the rear end of the drawer ride. Beyond the track portion, the strip is again bent downward- 55

ly at 34 for attachment to the stove framework. A roller 36 is mounted upon the vertical body portion of strip 30 and similarly another roller 37 is also mounted upon this strip but positioned closer to the front of the oven. These two rollers are in different horizontal planes and so spaced that there is guiding clearance between them for the flange 23 of the drawer. The flange 23 thus serves as both guiding and supporting means for the drawer as it is moved into and out of the broiler compartment. This flange is also provided with an upturned portion 42 at the extreme inner end of the drawer which serves as a stop when it engages the roller 36 in the forward position of the drawer. This represents the normal movement of the drawer and when in this position, the pan is practically clear of the oven so that it may be readily removed. It will be noted that the side walls of the drawer are quite shallow and that the pan, even in its lowermost position, is supported above the side wall and consequently may be easily grasped at the sides and removed.

When it is desired to withdraw the drawer farther, the front end is tilted upwardly to cause the stop member 42 to be depressed and to clear the lower surface of roll 36 and then the drawer may be withdrawn so that the pan will entirely clear the oven compartment. The rollers 37 and 28 are of such size and are so positioned that the roller 28 will not pass under the roller 37. Consequently there is no danger, even when the drawer has been removed to its extreme outward position, of having the same fall out of the oven unexpectedly. To completely remove the drawer, the inner end thereof is raised so that the roller 28 may be moved over the roller 37, and the entire drawer may be withdrawn completely.

Mounted in the front member of the drawer is a shaft 52 adapted to be rotated in suitable bearings 54 and 55 which are formed in the plates 16 and 18 respectively by punching the same and bending over the edges of the material to form a bearing surface. A pinion 51 is fixed to shaft 52 by any suitable means and is engaged by a spring detent 56 which is mounted upon the bent over top surface of the sheet 18. This detent yieldingly engages the teeth of the pinion and serves to hold the same in any position in which it is left. A large segmental gear 58 is rotatably mounted upon a shaft 59, which is carried in similarly formed bearings in both front and rear walls 18 and 20 of the drawer, and which extends the entire distance between these two walls. The teeth of this gear are adapted to engage the pinion 51. Projections 60 are formed at each end of gear 58 to serve as stop members when they abut against the pinion 55 in either extreme position of the gear.

60 A lever 61 is fixed to the shaft 59 within the compartment formed by plates 16 and 18, and is pivoted at one end to two operating links 62, one of these links being placed upon each side of the lever and spaced apart a predetermined distance. 65 The links 62 in turn are pivoted to one of a pair of pan supporting arms 63, 64, which in turn are pivoted at 65, 66 to the plate 18. In order that the pivot points shall not extend into the oven or interfere with the removal of the pan, 70 depressions 67, 68 are formed in plate 18 of such a depth that the pivots are indented from the surface of the plate 18. The arms 63 and 64 are formed with intermeshing gear teeth 69, 70 at their adjacent ends and thus it is insured that 75 the two arms will move in unison, for any move-

ment imparted to the arm 63 by lever 61 will be transmitted to and will produce a similar movement in arm 64.

It will be understood that the thickness of the parts used in the operating mechanism is necessarily restricted to relatively narrow limits inasmuch as it is desirable to keep the width of the compartment formed by plates 16 and 18 as small as possible. Therefore the invention also includes a means for insuring against any possibility of the teeth of the intermeshing faces of arms 63 and 64 slipping out of engagement with each other. This means comprises projections 72 formed on each link 62 and so positioned as to overlie, on each side, the portion of the gear faces 69, 70 which are in engagement with each other. This support on each side of the gear teeth effectively insures against any possibility of slippage or of the gears becoming misaligned.

Slots 74 are formed in plate 18 and are adapted to receive projecting lugs 75 formed on pan 16, which lugs rest upon the supporting arms 63, 64. The slots serve as vertical guides for the pan and keep it in alignment as it is moved up and down in response to a raising or lowering movement of arms 63, 64. To provide against a possible bending of arms 63 and 64, brackets 77 are mounted upon the inner surface of plate 18 and are spaced therefrom a distance just sufficient to provide for the vertical movement of the arms 63, 64 but will effectively prevent any horizontal movement or bending of the arms, such as might be caused by a careless person in forcing the lugs 75 against the operating arms in positioning the pan within the drawer.

35 The mechanism at the inner end of the drawer is substantially similar to that at the outer end, with the exception of the operating pinion and segmental gear. The shaft 59 extends into the rear wall of the drawer and consequently it is only necessary to provide a lever 81 pivoted to two operating links 82 which in turn are pivoted to one of the inner pan supporting arms 83 and 84. These arms are pivoted at 85, 86 to the inner plate 20 of the inner wall, which is similarly provided with depressions 87, 88 so that the pivot point will not extend into and interfere with the positioning of the pan. Links 82 are formed with projections 89 which overlie the intermeshing gear faces of arms 83 and 84 and perform the same function as projections 72 at the outer end of the drawer. Reinforcing brackets 90 are also positioned at the inner end and function in the same manner as do the brackets 77 at the outer end. Slots 91 formed in plate 20 provide for guiding the pan during its vertical movement.

50 The operation of the pan elevating mechanism is as follows: In response to a turning movement of handle 50, the pinion 51 causes rotation of a segmental gear 58 which in turn imparts a rotational movement to the shaft 59. Levers 61 and 81, fixed to shaft 59 cause the movement of the operating links 62 and 82 respectively, which in turn cause the arms 63 and 83 to rotate about pivot points 65 and 85 respectively. In response to this movement, the arms 64 and 84 are likewise caused to rotate the same amount about their pivot points 66 and 86 respectively. This causes the outer ends of all the arms to move either up or down, in the same direction, and to the same degree. Thus the pan, which is supported by lugs 75 from the four operating arms, is caused to be raised or lowered, the same amount at every point and hence is maintained horizontal throughout its extent of vertical movement.

In the arrangement just described, the single handle 50 serves two purposes. It provides a convenient means for moving the drawer laterally of the oven and at the same time it comprises the external means for vertically positioning the pan. It is of course obvious that these two functions are entirely distinct and independent, and therefore a modified form of the invention is illustrated in Figs. 5 and 6 wherein separate handles 100 and 101 are provided, the former being mounted upon the shaft 52 (not shown) and adapted to be rotated to vertically position the pan, and the latter being fixed to the front face of the stove and used for moving the drawer laterally. The handle 100 is relatively small and the operator therefore will normally not attempt to withdraw the drawer by grasping this handle but will pull the drawer out by means of the larger handle 101.

Another modified construction has also been illustrated in Figs. 7 and 8 wherein a dial 104 is mounted upon shaft 52 (not shown), while the larger handle 105 serves to move the drawer laterally of the oven. The two handles are positioned relatively close together as shown so that when it is desired to move the dial 104 to adjust the pan vertically, the handle 105 may be used as a convenient rest for the hand so as to make it easier to turn the dial with one or two fingers. Suitable indicating means such as a pointer 106 may be provided on the dial to indicate the position of the pan elevating mechanism. If desired, the face of the drawer may be calibrated in terms of the vertical position of the pan, and thus it is possible to position the pan at any desired height, without opening the drawer, by setting the indicator on the dial to the desired point on the scale.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a stove having an oven compartment, a slidable drawer having a hollow front closure and a hollow rear supporting wall, a foodstuffs supporting pan, and mechanism within said drawer for effecting vertical travel of said pan within the drawer, said mechanism being operably mounted within said front closure and rear supporting wall and operable independently of the sliding movement of the drawer.

2. In a stove having an oven compartment, a slidable drawer having a front closure, a foodstuffs supporting pan, elevating mechanism within the drawer for supporting the pan, means for enclosing said mechanism to prevent access of undesired matter thereto, and means carried by the drawer and operable from the exterior of said closure for actuating said mechanism.

3. In a stove provided with a broiler compartment, the combination of a drawer provided with a flange on its side walls, cooperating rollers carried by the walls of said compartment, a broiler pan, a support for said pan mounted in the hollow end walls of said drawer, and means for adjusting said support, said means being protected against contact with the food and comprising an operating member positioned exteriorly of said compartment and carried by said drawer.

4. A broiler compartment for a range comprising a removable drawer provided with a front wall forming a closure for said compartment, an ad-

justable handle carried by said wall, a pair of adjustable pan supporting arms formed at adjacent ends with intermeshing gear faces, and means establishing an operating connection between said handle and said arms, including links 5 pivoted to one of said arms and formed with a projection adapted to overlap said intermeshing gear faces in all positions of the latter.

5. A broiler compartment for a range comprising a removable drawer provided with front and rear hollow walls, pan supporting arms carried in said walls, a broiler pan, and means for adjusting said arms to move said pan vertically including a rotatable shaft having a pinion, a segmental gear meshing with said pinion, a shaft 15 carrying said segmental gear and extending from said front to said rear wall, and connections within said walls for linking said shaft to said arms.

6. In a stove of the character described, a 20 broiler compartment and a broiler pan, the combination of a drawer having front, rear and side walls, the front wall forming a closure for said compartment, the side walls being bent over to form a flange, rollers mounted on the walls of 25 said compartment adapted to engage said flange to provide for the lateral movement of said drawer into and out of said compartment, a handle for said drawer fixed to a shaft carried in said front wall, a pinion on said shaft, a segmental gear meshing with said pinion, a lever attached to said gear, pivoted arms operatively associated with said lever and adapted to raise or lower said broiling pan in response to a rotating movement of said handle. 35

7. A broiler compartment for a range including an adjustable handle, a pair of pivoted arms formed with intermeshing gear faces, a broiler pan supported on said arms, an operating mechanism joining said handle to said arms and providing for vertically positioning the pan within the compartment, and means for insuring intermeshing relation of said gear faces throughout the extent of their movement. 40

8. In a broiler compartment of a stove, a 45 broiler pan, a pair of pivoted pan supporting arms formed at their adjacent ends with intermeshing gear faces, and means for causing rotation of said arms about their pivots to raise or lower said pan, said means also adapted to overlie said 50 intermeshing gear faces to insure intermeshing relation thereof at all times.

9. In a broiler compartment of a stove, a pair of pivoted pan supporting arms formed at their adjacent ends with intermeshing gear faces, an 55 enclosing housing for said arms, the walls of said housing being slotted to form guides, a broiler pan provided with lugs extending through said slots and resting on said arms, and means for rotating said arms to vary the positioning of said 60 pan.

10. In a stove having an oven compartment, a slidable drawer, supporting arms mounted on the end walls of said drawer and formed at their adjacent ends with intermeshing gear faces, one 65 of said end walls constituting a closure for said compartment, a broiler member supported on said arms, means for adjusting said arms to position the broiler member vertically within the compartment, and yieldable means enclosed within 70 one of said end walls for maintaining the broiler member in any selected position.

11. In an oven, a removable unit comprising the combination of a vertically adjustable food-supporting member, an oven closure member, 75

and elevating mechanism for raising and lowering said food-supporting member, said elevating mechanism being completely concealed within said oven closure member.

- 5 12. In an oven, a removable unit comprising the combination of a vertically adjustable food-supporting member, an oven closure member, an elevating mechanism for raising and lowering said food-supporting member, and control means positioned exteriorly of said oven closure member for actuating said elevating mechanism, said elevating mechanism being completely concealed within said oven closure member.
- 13 13. An adjustable broiler for a household oven, and the like, comprising the combination of a horizontally slidable oven door, a vertically adjustable food-supporting rack carried by said door, and mechanism completely concealed within said door for vertically moving said rack.
- 14 15. In a stove having an oven compartment, a drawer slidably mounted in said compartment, a foodstuffs supporting pan, elevating mechanism carried by said drawer and supporting said pan and means carried by said drawer enclosing said elevating mechanism to prevent access of undesirable matter thereto.

14. An adjustable broiler for a household oven, and the like, comprising the combination of a horizontally slidable oven door, a vertically adjustable food-supporting rack carried by said door, mechanism completely concealed within said door for vertically moving said rack, and an operating handle on the exterior of said door and connected to said mechanism.

15. In a stove having an oven compartment, a drawer slidably mounted in said compartment, a foodstuffs supporting pan, elevating mechanism carried by said drawer and supporting said pan and means carried by said drawer enclosing said elevating mechanism to prevent access of undesirable matter thereto.

BERTRAND B. KAHN.
